UNITED STATES PATENT OFFICE.

LOUIS TONETTI, OF PARIS, FRANCE, ASSIGNOR TO LINCOLN HAUSMANN,
OF NIAGARA FALLS, NEW YORK.

DESIGN FOR A PLAQUE.

SPECIFICATION forming part of Design No. 22,522, dated June 13, 1893.

Application filed May 4, 1893. Serial No. 473,024. Term of patent 14 years.

To all whom it may concern:

Be it known that I, LOUIS TONETTI, a citizen of the Republic of France, residing at No. 6 Rue Cassini, in the city of Paris, France, have invented and produced a new and original Design for Historical Plaques; and I do hereby declare the following to be a full, clear, and exact description of the same, reference being had to the accompanying drawing, forming a part thereof.

The leading feature of my design consists of a center-piece or medallion and surrounding segmental sections; the center-piece contains a graphic representation, or a representation in intaglio or relief, of Christopher Columbus, and the surrounding segmental sections contain the leading or noted incidents in his life.

In the present instance, the letter A represents a medallion which contains or has produced within it the bust of Christopher Columbus. The said medallion is surrounded by a circular rib, B. Around said rib are represented or arranged segmental sections 25 or spaces C divided by radial lines D. Within said sections or spaces are produced, representations of several of the most noted incidents in the life of Columbus, together with a representation of the flag and shield of the 30 United States and other devices. The upper section or space, above the medallion, con-

tains, centrally, a representation of the United States flag, shield and fasces; and at each side thereof is a representation of an international building at Chicago. In the section or space 35 below the medallion, is a representation of Columbus as he first discovered the New Continent from the deck of his ship; on the right, in its appropriate section or space, is a representation of the landing or arrival of Columbus on the New Continent, and at the left, in its assigned section or space, is a representation of the return of Columbus and his reception by King Ferdinand and Queen Isabella of Spain.

My design is circular in form of concavo-convex shape, with the medallion and the representations surrounding the same in relief. A border surrounds the segmental sections, and opposite the respective sections is 50 a space for inscribing suitable descriptive words.

What I claim is—

The design for plaques, substantially as shown and described.

In testimony whereof I affix my signature in presence of two witnesses.

LOUIS TONETTI.
